UNITED STATES PATENT OFFICE.

IRA R. SELTZER, OF WATERBURY, CONNECTICUT, ASSIGNOR TO THE GORDON ELECTRIC MANUFACTURING COMPANY, OF WATERVILLE, CONNECTICUT, A CORPORATION.

SNAP-SWITCH MECHANISM.

Application filed August 26, 1921. Serial No. 495,679.

To all whom it may concern:

Be it known that I, IRA R. SELTZER, a citizen of the United States, residing at Waterbury, in the county of New Haven and State 5 of Connecticut, have invented a new and useful Improvement in Snap-Switch Mechanisms; and I do hereby declare the following, when taken in connection with the accompanying drawings and the characters of 10 reference marked thereon, to be a full, clear, and exact description of the same, and which said drawings constitute part of this application, and represent, in—

Fig. 1 a view in side elevation of one form 15 which my improved snap-switch mechanism may assume.

Fig. 2 a plan view showing the same mechanism as installed in a portion of a tubular housing.

20 Fig. 3 a view thereof in side elevation.

Fig. 4 a view thereof in longitudinal section on the line 4—4 of Figure 3, showing the under side of the mechanism.

25 Fig. 5 a view thereof in longitudinal section on the line 5—5 of Figure 2, with the switch-mechanism in its open position.

Fig. 6 a corresponding view with the switch-mechanism in its closed position.

30 Fig. 7 a view in transverse section on the line 7—7 of Figure 6.

Fig. 8 a detached view in elevation of the trigger-like operating-member of the switch.

Fig. 9 an edge view thereof.

35 Fig. 10 a reverse plan view of the insulating switch-base as stripped.

My invention relates to an improved switch-mechanism of the so-called "snap-switch" type, such as are extensively used for controlling electric-light circuits, small 40 power-circuits such as vacuum-cleaner circuits, vibrator circuits, etc., the object being to simplify and improve the convenience of such switches, as well as to more readily indicate whether they are in their open or 45 closed positions, or "off" or "on."

With these ends in view, my invention consists in certain details of construction and combinations of parts as will be hereinafter described and pointed out in the claim.

50 In carrying out my invention, as herein shown, I employ a trigger-like, rocking operating-member 11 having its upper edge 12 serrated and located in a longitudinally-arranged slot 13 in an oblong, insulating 55 switch-base 14, the upper face 15 of which

is rounded. The said part 11 is provided about midway of its length with a short, transverse shaft or pin 16, upon which it rocks back and forth, the ends of this pin being set into aligned bearing-grooves 17 60 intersecting the inner end of the slot 13 and formed in the bottom wall of an oblong chamber or recess 18 formed in the lower face of the insulating switch-base 14 for the reception of a sheet-metal switch-frame 19 65 adapted to fit into the said recess 18, in which it is held by screws 20 and 21 entered into it through the base 14 which is seen to be formed with a transverse passage intersecting its outer and inner faces and consisting of the slot 13 and the chamber 18. The ends of the shaft 16 are held in the bearing-grooves 17 by the body-part of the frame 19, as clearly shown in Fig. 5. The lower end of the said operating-member 11 70 is formed with a slot 22 adapting it to be engaged with the slotted upper end of a sheet-metal switch-rocker or actuator 23 having a perforation 24, receiving a small tongue 25 formed upon the inwardly-turned arm 26 of the switch-frame 19, the rocker or actuator 23 rocking back and forth upon the said tongue 25, as upon a pivot. The lower end of the part 23 is bent to form a hook 27 coacting with a switch 28 to throw 75 the same into its open, or "off," position, as shown in Figure 5, and into its closed, or "on," position, as shown in Figure 6, the switch having a shank 29 sliding back and forth through a bearing-opening 30 in the 80 arm 31 of the frame 19, and encircled by a spring 32, which throws the switch in one direction or the other, as it passes its dead-center with relation to the tongue 25 of the part 23. As the switch is thrown into its 85 closed position, its contact-arms 33 (Figure 4) engage with contact-plates 34 and 35 inserted into the lower face of the insulating base 14 and connected with terminals 36 and 37 carrying binding-screws 38 for the attachment of the conductors 39.

As shown, the switch-mechanism described is fastened by screws 40 to, and depends from, the central portion of a transversely-bowed mounting-plate 41 secured by screws 42 passing through its ends to the tubular handle 43 of a vacuum-cleaner the said handle being formed in its upper face with a longitudinal installation-slot 44 covered by the plate 41 and provided to permit the en- 110

trance of the switch-mechanism into the handle, and the said plate being formed with a slot 45 for the upward projection through it of the outer end of the trigger-like operating-member 11.

I claim:

The combination with the tubular handle of a vacuum-cleaner, the said handle being formed on its upper face with a longitudinal installation-slot, of a transversely-bowed, slotted mounting-plate superimposed upon the said handle to cover the said installation-slot and extended beyond the ends thereof for being attached to the upper face of the said tubular handle, an oblong insulating switch-base having its upper face rounded to fit the concave inner face of the said plate to which it is fastened and having its inner face formed with a recess or chamber

communicating with the slot in the said plate, a switch-frame located in the said chamber, a snap-switch mechanism mounted in the said frame so as to project inwardly therefrom, and a rocking operating-member connected with the said mechanism for the operation thereof and projecting outwardly through the said base and the slot in the mounting-plate, and pivotally mounted on a trunnion interposed between the bottom of the said switch-frame and the bottom of the chamber in the said switch-base.

In testimony whereof, I have signed this specification in the presence of two subscribing witnesses.

IR A R. SELTZER.
